UNITED STATES PATENT OFFICE.

ROBERT E. OLSEN, OF FOREST HILLS, NEW YORK.

PHOTOGRAPHIC BUTTON.

Application filed March 30, 1927. Serial No. 179,465.

This invention relates to photographic devices.

The general object of this invention is to provide a photographic button or medalion having novel features of construction.

Another object of this invention is to provide an improved photographic button having a fluid tight joint at the juncture of the sensitized photographic sheet and the button frame.

Still another object of the invention is to provide an improved photographic button so constructed as to provide a smooth flat back surface.

Other objects and advantages of this invention will be apparent from the following description taken in connection with the accompanying drawing wherein:

Fig. 1 is a front view of my improved photographic button showing the same developed and as having an image thereon.

Fig. 2 is a side elevation of my improved photographic button.

Fig. 3 is a rear face view of the photographic button shown in Fig. 1.

Fig. 4 is an enlarged section of my improved button taken on line 4-4 of Fig. 1.

Fig. 5 is a view similar to Fig. 4 showing the various elements which compose the button in a disassembled relationship, and

Fig. 6 is a greatly enlarged fragmentary section of the sensitized photographic plate.

Referring to the drawings by reference characters I have indicated my improved photographic button generally at 10. This photographic button 10 is particularly designed for use in conjunction with my improved coin actuated automatic photographic camera shown and described in my co-pending U. S. patent application Serial Number 41,033, filed July 2, 1925, but it may be used in other machines and for other purposes for which it is suitable.

The button 10 is preferably circular as shown and comprises a frame 11, a sensitized photographic plate 12, and a back 14. The photographic plate 12 is provided on one face with a sensitized photographic emulsion 12^a as shown in Fig. 6, and may be provided on its other face with a coating of waterproof material of dark color 12^b. This coating has many advantages, one is that it enables the back to be readily distinguished from the sensitized face when the button is being assembled.

As shown in the accompanying drawing, the frame 11 is made from a single piece of material and comprises a face portion 15 having a central downwardly extending collar 16 which forms a recess 17, and which is bent centrally again at substantially right angles to form another planar flange 18 which lies in a plane substantially parallel to the plane of the face portion 15 and which forms an aperture or sight 19. The outer periphery of the face 15 is bent downwardly to form a collar 20 (see Fig. 5) the lower portion of which in the completed button as shown in Fig. 4, is bent inwardly to form a resilient flange 21 which bears against the back plate 14 and tightly clamps the sensitized photographic plate 12 against the under face of the flange 18. By proportioning the parts as shown and by use of more or less resilient material the sensitized photographic plate 12 bears against the under face of the flange 18 and the emulsion is slightly indented and highly compressed to make a fluid tight joint which will, during the process of developing and rinsing, prevent fluid from passing into the interior chamber 22, which is formed in the frame 11 by the various elements of the button.

The peripheral edge of the sensitized photographic plate 12 is bent to form a conical flange 23 and the peripheral edge of the back plate 14 is similarly bent to form a flange 24. By so forming the peripheral edges of the plate 12 and the back 14 the flange 21 of the frame 11 may abut the back 14 in such a manner that the outer face of the flange 21 does not project into the plane of the back 14, so that no obstruction projects beyond the outer face of the back 14. This greatly facilitates stacking the buttons 10 upon one another and forms a smooth surface upon which the buttons may be moved while in the photographic machine.

The recess 17 at the top of the button forms a compartment in which developing fluid is placed during the developing process and by varying the depth of the recess 17 the quantity of developing fluid used may be varied.

The various elements which form my improved button are preferably made of sheet metal and the frame which may be of resilient metal provided upon its exposed surfaces with designs or may be left plain as shown

in the drawing. The frame and the back plate or only the frame may be plated with nickel, silver, gold or any other substance to appeal to the artistic sense if so desired.

5. If desired the sensitized plate 12 alone may be used for certain uses. In this event the flange 23 serves to hold the developing and washing fluids.

From the foregoing description it will be 10 apparent that I have provided an improved form of photographic button which is simple in construction, durable, and wherein means is provided for holding a developing fluid during the developing process and wherein 15 means is provided for forming a fluid tight joint between the sensitized photographic plate and the frame of the button.

What I claim is:

1. A button including a frame and a sensitized plate, said plate including a planar body portion having an upwardly directed peripheral edge, said frame including a top portion and a bottom portion, said top portion engaging said sensitized plate and 25 means to hold said frame on said plate.

2. In a device of the class described, a plane, round, disc-like sensitized plate having an integral flange thereon, said flange being continuous and arranged at an angle 30 to the plane of the disc to form a cup, the plane portion of said plate having an emulsion thereon.

3. A button including a frame, a sensitized photographic plate and a back, said 35 frame comprising a continuous front portion engaging said plate and a rear portion engaging the back of said plate and in the

same plane therewith, the top of said frame being disposed above the top of said plate.

4. A button including a frame, a sensitized photographic plate and a back, said 40 frame being made from a single piece of material, said frame comprising a face portion, inner and outer cylindrical collars on said face portion and extending at substantially right angles to the face portion, the inner collar being bent inwardly to form a flange which lies in a plane substantially parallel to the plane of the face portion, said outer collar being bent inwardly to clamp 50 said photographic plate in tight engagement with said first mentioned inwardly bent flange, thus forming a water tight joint between said inwardly bent flange and said photographic plate, said back being retained 55 in tight contact with said photographic plate by said second mentioned inwardly bent flange.

5. A button including a frame, a sensitized front plate and a planar back plate, 60 said front plate and said back plate having their peripheral edges bent to form conically shaped peripheral flanges, said frame comprising a face portion, and portions bent to form inturned front and back flanges, said 65 front flange being bent to form a flange which engages the said face portion, said back flange being in clamping engagement with said back plate, said back flange being disposed above the plane of the back plate. 70

In testimony whereof, I hereunto affix my signature.

ROBERT E. OLSEN.
